(57) **CLAIM**

We claim the ornamental design for building structure for a carwash with equipment, as shown and described.

DESCRIPTION

FIG. 1 is a front elevational view of a building structure for a carwash with equipment showing our new design;
FIG. 2 is a right side elevational view thereof;
FIG. 3 is a rear elevational view thereof;
FIG. 4 is a left side elevational view thereof; and
FIG. 5 is a top plan view thereof.

FIG. 6 is an enlarged detail of the corresponding portion of FIG. 1;

FIG. 7 is an enlarged detail of the corresponding portion of FIG. 2;

FIG. 8 is an enlarged detail of the corresponding portion of FIG. 2;

FIG. 9 is an enlarged detail of the corresponding portion of FIG. 2;

FIG. 10 is an enlarged detail of the corresponding portion of FIG. 4;

FIG. 11 is an enlarged detail of the corresponding portion of FIG. 4; and,

FIG. 12 is an enlarged detail of the corresponding portion of FIG. 4.
